Attorney

UNITED STATES PATENT OFFICE.

ROBERT T. CUMMINGS, OF SPOKANE, WASHINGTON.

SLEDDED SCOOP.

Application filed June 28, 1926. Serial No. 118,933.

My present invention relates to an improved sledged scoop or excavating implement of the pivoted, drag-scraper type for use in leveling, filling and other earth engineering or grading work. The improved implement of my invention comprises a horse-drawn sled, or spaced runners, in which the scoop is pivoted, adapted to be retained in loading position, and also adapted to be up-ended or overturned for the dumping operation, after which the overturned scoop is conveyed to the place of excavation and manually returned to operative position for loading. Means are provided for guiding the pivoted scoop as it is being adjusted for loading, and bracing it against lateral movement or displacement during the loading operation as well as during the time it is being used to convey a load to the dump. The invention consists in certain novel combinations and arrangements of parts whereby a well braced, strong, and durable implement of this character is provided, which may be operated with facility, and in which worn parts may be replaced with convenience and in an inexpensive manner.

In the accompanying drawings I have illustrated one complete example of the physical embodiment of my invention wherein the parts are combined and arranged according to the best mode I have thus far devised for the practical application of the principles of my invention.

Figure 1 is a perspective view of an implement embodying my invention and shown in operative position for loading.

Figure 2 is a vertical, transverse, sectional view through the implement of Figure 1.

In carrying out my invention I preferably utilize a drag-frame or sled, comprising a pair of spaced, longitudinally extending runners 1 and 2 fashioned from angle plates, and rigidly joined at the rear of the implement by a transversely extending angle brace 3 bolted at its ends to the rear ends of the runners.

Each runner is provided at its underside with a wear plate or shoe 4, which is fashioned with an upright extension 5 and bolted or otherwise secured to the runners, for replacement when worn. The worn shoes or wear plates may readily be removed when required and fresh shoes substituted therefor to insure durability and long life to the implement.

The pivoted scoop is of the standard type

having a bottom plate 6, rear upright plate 7 and a forwardly turned upper flange 8, with the two end walls or sides 9, 9. On the outer sides of the end walls 9 are secured transversely extending, alined trunnions 10 that are journaled in bearing blocks 11, secured at the undersides of the top bars of the runners, to permit the scoop to be tilted as desired and to be overturned or upended in dumping its load.

The implement is drawn by one or two horses which are hitched thereto by means of the attaching hooks H, H, bolted to the outer sides of the runners and located at the front thereof as seen in Figure 1.

For guiding the scoop as it is being adjusted on its pivots, and to retain it against lateral movement and against twisting strains on the trunnions, I provide forked guide lugs 12 bolted at the exterior of the end plates or walls of the scoop and projecting beyond the forward edges of the walls. These forked guide lugs co-act with a pair of vertically arranged guide plates 13, one of which is bolted at the forward end of the runners, and they are provided with arcuate edges on lines struck from the axes of the trunnions as centers. As the scoop partakes of a pivotal movement with relation to the drag frame or sled the forked lugs ride over the arcuate edges guiding the movement of the scoop and preventing any wobbling or lateral displacement of the scoop.

At the rear of the scoop an operating handle 14 is secured by brackets or braces 15, and a cord or cable 16 is attached near the end of the handle for use when the latter is being used as a lever to return the overturned scoop to normal working position.

The scoop may be turned on its pivot for adjusting the front cutting edge of the bottom-plate 6 with relation to the ground level, by the use of a lever 17 rigidly secured at the rear of the sled, and provided with a spring actuated latch lever 18 and latch 19 for co-action with an arcuate rack 20 bolted to the scoop. By the use of the lever 17 the sled also may be tilted forwardly on its shoes in the manipulation of the implement for loading, and dumping the load. The handle 14 is of course used for tilting the scoop, when it is unlatched, to load it, and bring the loaded scoop to position for conveying the load to the dumping place.

Having thus fully described my inven-

tion, what I claim as new and desire to secure by Letters Patent is—

The combination with a pair of rigidly connected runners each having an arcuate

5 guide-plate, of a scoop pivoted in the runners and provided with forked guide lugs at its front edges for co-action with said plates,

an operating handle attached to the scoop, a hand lever attached to one of the runners, a rack on the scoop, and a latch device carried by said hand lever.

In testimony whereof I affix my signature.

ROBERT T. CUMMINGS.
